UNITED STATES PATENT OFFICE.

CHARLES W. SCHULTZ, OF DETROIT, MICHIGAN, ASSIGNOR OF ONE-HALF TO EDWARD A. SWEENEY, OF DETROIT, MICHIGAN; RICHARD E. SCHULTZ ADMINISTRATOR OF SAID CHARLES W. SCHULTZ, DECEASED.

CUSHION-SPRING.

1,175,564.

Specification of Letters Patent. Patented Mar. 14, 1916.

Application filed February 26, 1912. Serial No. 679,828.

To all whom it may concern:

Be it known that I, CHARLES W. SCHULTZ, a citizen of the United States, and a resident of Detroit, in the county of Wayne and State 5 of Michigan, have invented a new and useful Cushion-Spring, of which the following is a specification.

This invention relates to cushion-springs for seats and seat-backs for vehicles, and 10 particularly for automobiles; and its object is to provide a construction of which predetermined parts shall be very yieldable and very resilient.

This invention consists of a frame, a series 15 of helical-springs mounted thereon in parallel, longitudinal and transverse rows, in combination with flat, spiral springs extending from the outer ends of the helical springs and curving inward to a point of 20 connection with the supporting frame.

It further consists in combination with such spring construction, of a series of resilient connectors extending between the flat, spiral springs.

25 In the accompanying drawings Figure 1 is an elevation of a seat-back spring with a portion of the upholstering removed to show the metal construction. Fig. 2 is a vertical section of the construction shown in Fig. 1. 30 Fig. 3 is a front elevation of a slightly modified form of spring construction. Figs. 4 and 5 are vertical sections showing slight modifications of construction. Fig. 6 is a plan and Fig. 7 an edge view of the spring ribbon formed by twisting spring wire into a flat spiral. Fig. 8 is a plan and Fig. 9 a 35 vertical section of a seat-spring embodying the invention.

Similar reference characters refer to like 40 parts throughout the several views.

Automobile builders have been experimenting for several years in order to obtain cushion-springs which will be satisfactory to the discriminating public. The objections to the present type of cushion are directed chiefly against the hardness of the upper portion of the back cushion and the front edge of the seat cushion, which hardness results in the jarring and shaking of 45 the passenger because of the unevenness of the road over which the vehicle is traveling. This hardness of the upper portion of the seat back cushions often causes headaches 50

and dizziness. The present construction is especially adapted to produce a seat back 55 spring which will render the cushion immediately back of the shoulders, neck and head of the passenger so yielding that all jars and other shocks will be substantially obviated. 60

Referring now to Figs. 1, 2 and 7, the frame upon which the cushion spring is erected is composed of horizontal bars 1 and vertical bars 2. Secured to the frame are the helical springs 3, which are preferably 65 arranged in horizontal and upright rows. Extending from the bottom of the frame up over the outer ends of the helical springs 3 and connecting to the same, are spring wires 4, which connect to the lower ends of 70 the spring ribbons 5, which are formed by twisting spring wire into flat spirals 6, such as shown in Figs. 6 and 7. These spring ribbons 5 preferably extend upward and backward from the upper helical springs, 75 and then turn downward and inward until they connect to the upper bar 1 of the frame, preferably forming bows which extend to the rear of the frame, as shown in Fig. 2. Small coil springs 7 may be used to connect 80 between adjacent spring ribbons so as to furnish a support for the upholstering 8 and prevent the same from sagging down between the spring ribbons. The softness of this construction is such that the thickness 85 of the usual curled hair pad may be reduced from five or six inches to about two inches. Otherwise the upholstering of the cushion is about the same as that already in use. In the forming of these spring ribbons by bending the wire to produce flat spirals, it has 90 been found that the ribbon bends laterally more readily in one direction than the other. This is owing to the fact that the wire between adjacent loops is always at one edge, 95 as shown in Fig. 6. Because of this, the two springs which extend along the two sides of a row of helical springs 3, will be wound in opposite directions. Instead of the wire 4 extending from the bottom of the frame to 100 the upper helical spring, a ribbon of this flat, spiral winding may be used throughout the height of the cushion, as shown in Fig. 3, and it will also be seen that these flat ribbons 9 are wound right and left-handed. 105 Instead of connecting the upright spring-

ribbons by means of short coil springs, they may be connected across by means of flat, spirally-wound wire ribbons 10.

The flat spirally-wound ribbon here illustrated, is not only very yieldable when considered as a ribbon, but it expands or contracts longitudinally under very slight force. Therefore, when a spring of such construction is employed in a cushion for the back of a limousine, as shown in Fig. 5, a pressure on the upper helical spring sufficient to compress said spring, is accommodated by the flat spiral spring 11, which contracts readily. In this construction shown in Fig. 5, the back 12 of the limousine body extends above the cushion frame so that the flat spiral springs 13 will not extend back of the frame. In Fig. 4, the upright bars 14 are shown bent back at their upper ends and carry a cross bar 15 to which the rear ends of the flat spiral springs 16 connect. It will readily be seen that these seat-back springs can be given any desirable form, to suit the different constructions of vehicles in which they are to be employed.

In the construction shown in Figs. 8 and 9, a frame is shown formed of longitudinal bars 18 and transverse bars 19, upon which are mounted the helical springs 20, 21, 22, 23 and 24, which preferably decrease in length from the front to the back. Extending over these helical springs are flat, spiral springs 25, in pairs, which connect to the frame at its front edge and extend along on both sides of each transverse row of helical springs. Mounted on these helical springs 20 to 24 is a second set of helical springs 27, also in longitudinal and transverse rows, 40 but preferably of somewhat lighter wire than the springs below them. A second set of flat springs 28, in pairs, of this spirally-wound wire extends from the springs 25 upward, and then back over the tops of the springs 27, connecting to the same, and then down to the frame connecting to the rear ends of the flat springs 25. The usual upholstering 30 may be employed with this spring construction. Longitudinal bands 31 and 32 of this spirally-wound wire will extend along the tops of both the upper and the lower sets of springs, if desired. This construction is unusually yieldable and resili- 50 ent, and it is especially adapted for the seats of touring cars and other vehicles which are to be driven at high speeds over rough roads.

I claim.

1. A cushion spring construction comprising a frame, helical springs mounted thereon in transverse rows, a series of transverse rows of springs formed of flat coils of spirally-wound wire connected to the frame and having their loops slightly inclined from the general surface of the said

transverse rows of springs, two of said springs extending over each transverse row of helical springs and connected to the outer ends of the helical springs, one of the spiral springs connected to each row of helical springs being wound right-handed and the other left-handed, and resilient connections extending between adjacent flat spiral springs. 70

2. A cushion spring construction comprising a frame, helical springs mounted thereon in longitudinal and transverse rows, a series of transverse springs comprising flat spirals connected to the frame at both ends and extending upward over the outer ends of the helical springs, a second set of helical springs mounted upon the first and a second set of flat spiral springs connected to the first set of flat spiral springs and extending over the tops of the second set of helical springs, and longitudinal lines of flat spiral springs extending across the tops of the helical springs of both sets and connected to the transverse spiral springs. 75 80 85

3. A cushion spring comprising a frame, helical springs mounted thereon in transverse rows, a series of springs connected to the frame at both ends and connected to the helical springs at an intermediate point in the length of the said helical springs, a second set of springs connected to the second mentioned springs and extending over the outer ends of the helical springs. 90 95

4. A cushion spring comprising a frame, helical springs mounted thereon in transverse rows, a series of springs connected to the frame at both ends and connected to the helical springs at an intermediate point in the length of the said helical springs, a second set of springs connected to the second mentioned springs and extending over the outer ends of helical springs, and longitudinal springs joining the adjacent helical springs. 100 105

5. A cushion spring comprising a frame, helical springs mounted thereon in transverse rows, a series of springs connected to the frame at both ends and connected to the helical springs at an intermediate point in the length of the said helical springs, a second set of springs connected to the second mentioned springs and extending over the outer ends of helical springs, and a set of longitudinal springs joining intermediate portions of the adjacent helical springs. 110 115 120

6. A cushion spring comprising a frame, helical springs mounted thereon in transverse rows, a series of springs connected to the frame at both ends and connected to the helical springs at an intermediate point in the length of the said helical springs, a second set of springs connected to the second mentioned springs and extending over the outer ends of helical springs, a set of longitudinal springs joining the intermediate 125 130

- portions of the adjacent helical springs, and a second set of longitudinal springs joining the outer ends of the adjacent helical springs.
5. 7. A cushion spring comprising a frame, helical springs mounted thereon in transverse rows, a series of springs connected to the frame at both ends and also connected to the helical springs at an intermediate point in the length of the said helical springs, and a series of flat spiral springs connecting the outer ends of the helical springs.
10. 8. A cushion spring comprising a frame, helical springs mounted thereon in transverse rows, a series of springs connected to the frame at both ends and also connected to the helical springs at an intermediate point in the length of the said helical springs, a series of flat spiral springs connecting the outer ends of the helical springs, and longitudinal springs joining the adjacent helical springs.
15. 9. A cushion spring comprising a frame, helical springs mounted thereon in transverse rows, a series of springs connected to the frame at both ends and also connected to the helical springs at an intermediate point in the length of the said helical springs, a series of flat spiral springs connecting the outer ends of the helical springs, and flat longitudinal spiral springs joining the outer ends of adjacent helical springs.
20. 10. A cushion spring comprising a frame, helical springs mounted thereon in transverse rows, a series of springs connected to the frame at both ends and extending over the outer ends of the helical springs, a sec-
- ond set of helical springs mounted upon the first, and a second set of springs connected to the springs that extend over the first mentioned set of spiral springs and themselves extending over the outer ends of the second set of helical springs.
25. 11. A cushion spring construction comprising a frame, helical springs mounted thereon in a transverse row, a pair of springs extending over the outer ends of the helical springs of each row, each of the pair of springs comprising a portion formed of a flat coil of spirally-wound wire and extending in an arched form from the outer end of the helical spring at one end of the row to the frame, the flat spirally-wound portion of one of the springs being wound right-handed and the flat spirally-wound portion of the other being wound left-handed whereby a balanced structure is produced.
30. 12. A cushion spring comprising a frame, helical springs mounted thereon in transverse rows, a series of flexible members connected to the frame at both ends and connected to the helical springs at an intermediate point in the length of the said helical springs, and a set of springs operatively connected to the frame at both ends and extending over the outer ends of the helical springs.

In testimony whereof I have signed this specification in the presence of two subscribing witnesses.

CHARLES W. SCHULTZ.
